Primary Examiner — George D. Kirschbaum*Assistant Examiner* — Joseph J Kukella(74) *Attorney, Agent, or Firm* — Baker, Donelson,
Bearman, Caldwell & Berkowitz PC(57) **CLAIM**

The ornamental design for a receiver for a pet collar, as shown and described.

DESCRIPTION

FIG. 1 is a first perspective view showing our new design for a receiver for a pet collar, taken from a right front angle. FIG. 2 is a second perspective view of the receiver for a pet collar of FIG. 1, but taken from a left front angle.

FIG. 3 is a third perspective view of the receiver for a pet collar of FIG. 1, but taken from a top right angle. FIG. 4 is a top view thereof.

FIG. 5 is a bottom view thereof.

FIG. 6 is a front elevational view thereof.

FIG. 7 is a back elevational view thereof.

FIG. 8 is a left side elevational view thereof; and,

FIG. 9 is a right side elevational view thereof.

The structural features shown in broken lines have been shown for the purpose of illustrating portions of the receiver for a pet collar that form no part of the claimed design.

The broken lines for the trademark "PetSafe" are included for the purpose of illustrating environment and form no part of the claimed design.

1 Claim, 3 Drawing Sheets(56)
